UNITED STATES PATENT OFFICE.

FERDINAND O. CROSS, OF BEDFORD, INDIANA.

DESIGN FOR A BUILDING-BLOCK.

SPECIFICATION forming part of Design No. 23,943, dated January 1, 1895.

Application filed April 5, 1894. Serial No. 506,509. Term of patent 7 years.

To all whom it may concern:

Be it known that I, FERDINAND O. CROSS, a citizen of the United States, residing at Bedford, in the county of Lawrence and State of Indiana, have invented a certain new and useful Design for Building Blocks or Stones, of which the following is a description, reference being had to the accompanying drawings, forming part of this specification.

Figure 1, is a view in perspective showing a block embodying my design. Fig. 2, is a cross section of the same on the line $x-x$, of Fig. 1.

Referring to the drawings, it will be seen that the leading feature of my design consists of a surface which shows a number of irregularly disposed projections with intervening depressions. Some of the projections as will

be seen from the drawings are rounded and smooth while others are rough and irregular, but all are so disposed with relation to each other as to present an appearance of compactness. The rounded projections are referred to in the drawings by the letter *a*, while the letter *b*, designates the rougher and less regular ones.

Having thus fully described my invention, I claim—

The design for a building block substantially as shown and described.

FERDINAND O. CROSS.
